UNITED STATES PATENT OFFICE

PAUL KUNIN AND ISAAC E. McELROY, OF MINNEAPOLIS, MINNESOTA; SAID McELROY
ASSIGNOR TO SAID KUNIN

WINDING DEVICE

Application filed August 23, 1928. Serial No. 301,545.

This invention relates to winding devices capable of wide general use, but especially adapted for coiling or winding human hair in connection with the process of effecting so-called permanent waves.

It is an object of our invention to provide a compact comparatively simple but highly efficient winding device, which may be driven from a suitable source of power and which will permit an operator to control the winding of the material upon a spool by the manipulation of a convenient operating handle or hand piece.

It is a further object to provide a winding device which is connectible to a source of power such as a motor, and which is provided with a slip clutch by which a uniform tension may be placed at all times upon material wound and by which fracture or damage to material will be prevented.

A further object is to provide a compact, portable winding device, the working parts of which are enclosed in a casing adapted to be held in the hand, especially adapted for beauty parlor work, to wind or coil locks of hair about a spool detachable from the winding shaft.

A still further object is to provide, in a device of the class described, a small casing in the form of a handle, having rotatably mounted therein a winding shaft adapted to receive a spool and mechanism disposed within said casing for connecting said winding shaft with a source of power, or for rigidly connecting said winding shaft with said casing and simultaneously disconnecting said winding shaft from said source of power, thereby enabling an operator to manually wind material on said rod by turning said casing to start the winding of material, or to automatically wind material.

It is a further object to provide in a device of the class described, means for varying the resistance or friction of the slip clutch to vary the tension which may be placed upon the material wound.

Another object of the invention is to provide a small, compact, portable device adapted to be held in the hand, capable of use as a winding device and moreover having an

other important use or function in connection with an attachment, namely, that of an automatic brush adapted to quickly and efficiently brush out human hair in connection with various treatments given by beauty shops.

These and other objects and advantages of the invention will be apparent from the following description, made in connection with the accompanying drawings, in which like reference characters refer to similar parts throughout the several views, and in which,

Fig. 1 is a side elevation of the device with some parts broken away on the winding spool and on the rear connection of the casing.

Fig. 2 is a view mostly in longitudinal section of an embodiment of the invention, some parts of the tubular sleeve constituting one of the clutch elements being broken away, and some parts being shown in section;

Fig. 3 is a cross section taken on the line 3—3 of Fig. 2;

Fig. 4 is a cross section taken on the line 4—4 of Fig. 2;

Fig. 5 is a cross section taken on the line 5—5 of Fig. 1, showing the slotted inner end of the winding spool and the manner in which a lock of hair, or other material is connected with the spool for winding;

Fig. 6 is a perspective view of the spool detached, having wound thereon a lock of hair for application within a tubular heating unit of a permanent wave machine;

Fig. 7 is a fragmentary view of the working end of my device converted into an automatic brush by means of a simple attachment, the brush being shown in cross section; and

Fig. 8 is a cross section taken on the line 8—8 of Fig. 7, showing the brush applied to human hair.

The embodiment of our invention illustrated in the drawings includes a straight tubular casing 8 constituting a handle for our device of rectangular cross section, provided with open ends, and having a slot 8^a extending longitudinally through one of its faces, hereinafter designated as its upper face and adjacent one end thereof. The left hand, or front end of said casing, is provided with a suitable bearing 9 which may slip in said end and be suitably secured thereto, and

the right or rear end of said casing is provided with a square plug 10 secured within casing 8 and having a threaded circular bore 10^a. A sleeve 11 externally threaded, screws into plug 10 and is adapted to abut at its inner end the shoulder 12^a of a clutch sleeve 12, which has a diminished outer portion telescoped within sleeve 11 and an enlarged cylindrical forward portion 12^b disposed within the medial portion of the casing 8 and mounted for free rotation within said casing. The clutch sleeve 12 may have its outer end slotted at 12^c for connection with a suitable toothed driving head 13^a rigidly connected with one end of a flexible driving member 13. The casing 14 for the flexible driving member may be swivelly connected to the plug member 10 in any suitable manner, such as in the manner shown in Fig. 1, wherein the casing for the flexible connection is provided with a flanged bushing Y swivelly connected with a swivel cup Z threadedly connected with member 11.

A winding shaft 15 is journaled in the bearing 9 and also in the medial portion of the clutch sleeve 12, said winding shaft projecting from the forward end of casing 8 and terminating short of the rear end of said casing, and slightly in advance of the slot 12^c in the clutch sleeve 12. Loosely mounted on shaft 15 within casing 8 is a slide block 16 of the width of said casing, and said block has connected therewith at its upper surface a finger piece 17 which is slidable forward or backwards in the slot 8^a provided in the upper face of the casing. A clutch collar 18 is pinned, or otherwise fixed, to shaft 15 at the forward side of the block 16 and is adapted to engage dogs 9^a rigidly carried by the bearing 9, the connection being made when shaft 15 is moved by the finger piece 17 to extreme forward position. At the rearward side of the block 16, a clutch collar 19 is pinned to shaft 15, said clutch collar preferably having ratchet teeth adapted to engage a co-operating clutch member for driving only in one direction. The clutch member 19 is adapted to be drivably connected with the forward end of a relatively small sleeve 20 loosely mounted on the rear portion of shaft 15 and having clutch elements 20^a at its forward end. The sleeve 20 is provided with a flange or head 20^b at its rear end and adapted to be abutted against a concave disc shoulder 21 formed in the clutch sleeve 12. A friction sleeve 21 of compressible material surrounds the sleeve 20 adjacent the rear end thereof and is adapted to be compressed between a pair of washers 22 also mounted on sleeve 20 at the opposite ends of friction sleeve 21. Friction sleeve 21 is of such diameter that its outer surface will snugly fit within the clutch portion 12^b of clutch sleeve 12, and an adjustable tensioning device is provided for compacting or compressing friction sleeve

21. It will be seen that a slip joint is provided between the sleeve 20 and the clutch portion 12^b of clutch sleeve 12 by the interposition of said friction sleeve 21. This may comprise a nut 23 having threaded engagement with the forward portion of sleeve 20, and a coiled spring 24 interposed between said nut and the forward compression disk 22. If desired, a set screw 25 may be provided in nut 23 to lock the same against displacement on sleeve 20. 70 75

In the bottom of slideable block 16, we prefer to provide a spring pressed ball 26 adapted to engage a pair of spaced notches or detents 27 in the bottom face of casing 8, to position shaft 15 properly in extreme forward or rearward positions and thereby cause driving engagement with the clutch members 20^a on sleeve 20 or with dogs 9^a rigidly connected with bearing 9, as the case 80 85 may be.

The projecting end of shaft 15 is provided with any suitable means for releasably and drivably retaining a hollow spool S thereon and as shown a bayonet joint is employed including a laterally projecting pin 28 on the forwardly projecting end of shaft 15 and a bayonet slot 28^a being provided in the inner end of the tubular body of spool S. Spool S is provided with front and rear flanges or disks 90 95 and the rear disk is preferably slotted at 29, to permit the swinging of a retaining bar 30, which bar at its rear end is hinged to the rear side of said disk.

In Figs. 7 and 8 an attachment is shown applied to the forwardly projecting end of shaft 15, converting the device into an automatic brush especially adapted to straighten out the hair and cleanse the scalp. The brush, indicated as an entirety by the letter B, comprises a sleeve 31 adapted to readily slip over projecting end of shaft 15, open at its inner end and having its outer end closed by any suitable means, such as a threaded plug 32. On sleeve 31 may be mounted a hard rubber sleeve 32 having radially projecting brush bristles 33 embedded therein or otherwise secured thereto, and the ends of said bristles being disposed in the form of a cylinder. The inner end of sleeve 31 is provided with a bayonet slot 31^a adapted to be readily connected with the pin 28 on shaft 15. 100 105 110 115 120

Operation

The operation of our device may be briefly described as follows:—

When one of the winding spools S is slipped over the projecting end of shaft 15 and drivably attached thereto by means of the bayonet joint, the device may be employed to automatically wind human hair for permanent waving. The outer end of a lock of hair is inserted between the retaining arm 30 and the sleeve of spool S and the hand piece 17 is pushed to extreme forward position, there- 125 130

by rigidly connecting shaft 15 with the handle or casing 8. The operator may then turn the device once or twice by hand, securing the lock to the spool. The hand piece 17 may then be moved to extreme rearward position causing clutch members 19 and 20 to intermesh and thereby driving shaft 15 through its clutch engagement with the driving sleeve 12. The slip clutch engagement is made 10 through the compressible friction sleeve 21 engaging the cylindrical forward portion 12^a of clutch sleeve 12. In winding human hair the tension of spring 24 is so regulated by manipulating adjustment nut 23 as to apply the degree of friction desired between the slip clutch parts. The position of the clutch sleeve 12 may be slightly varied as desired by screwing or unscrewing the externally threaded sleeve 11. The hair or other 15 flexible article may be wound upon spool S automatically controlled by the finger piece 17, handle or casing 8 being of such size that it can be conveniently grasped in the palm of the hand with the thumb applied to finger piece 17. In Fig. 2 the device is illustrated 20 on an enlarged scale.

When a lock of hair has been completely wound, the finger piece 17 is drawn forward, disconnecting the power upon winding shaft 30 15 and rigidly connecting said shaft with the casing to prevent unwinding of spool S. The spool may then be readily detached from the winding shaft, a lock of hair secured to the spool in any suitable manner and the coiled 35 hair on the spool may be inserted in a suitable tubular heater of a permanent waving machine.

Our device may be quickly and easily converted into an automatic brush by removing 40 the spool S and inserting the brush attachment B, sleeve 31 being secured by the bayonet joint to shaft 15. With the automatic brush attachment the hair may be quickly and evenly brushed, uniform tension being applied without damage to the hair, due to 45 the slip clutch driving mechanism of shaft 15. In beauty parlors it is desirable to brush the hair thoroughly before separating the locks for permanent waving and in treatment of the scalp for dandruff or other scalp 50 diseases, it is also desirable to thoroughly brush the hair and the scalp. With our device this may be done quickly and efficiently and without injury to the hair, assuming that 55 the device is regulated to interpose the proper friction between driving sleeve 12 and the sleeve 20.

While the embodiment of the invention illustrated is especially adapted for beauty 60 parlor work, it is, of course, obvious that the device is capable of wide general use as a winding reel or automatic brush.

The structure is compact, and the entire 65 device, as illustrated, may be conveniently

grasped by the hand and operated by the thumb.

It will, of course, be understood that various changes may be made in the form, details, arrangement and proportions of the parts without departing from the scope of 70 applicants' invention.

What is claimed is:

1. A device of the class described, comprising a handle, a shaft rotatably mounted in said handle, a driving element mounted in said handle and adapted to be connected to a source of power, and finger operated means for connecting or disconnecting said shaft and said driving element. 75

2. A device of the class described, comprising a handle, a shaft rotatably mounted in said handle, a driving element mounted in said handle adapted to be connected with a source of power, and means for connecting said shaft with said driving element with freedom for slippage. 85

3. A device of the class described, comprising a casing adapted to be held in the hand, a shaft rotatably mounted within said casing 90 and having a portion projecting beyond one end of said casing, a driving element mounted in said casing and adapted to be connected to a source of power, a slip joint between said driving element and said shaft, and means whereby said shaft may be connected with or disconnected from said driving element. 95

4. A device of the class described comprising a casing, a shaft rotatably carried by said casing and extending longitudinally thereof 100 having a portion projecting beyond said casing, means for connecting said shaft with a source of power and means for simultaneously disconnecting said shaft from said source of power and non-rotatably connecting said shaft with said casing. 105

5. A device of the class described, comprising a hollow handle, a shaft rotatably mounted within said handle and extending longitudinally thereof and having one of its ends 110 projecting beyond one end of said handle, a friction clutch rotatably mounted within said handle, a flexible driving member connected with said clutch, means for shifting said shaft longitudinally within said handle, and means for drivably connecting said shaft with said clutch when said shaft is shifted to one position. 115

6. A device of the class described, comprising a casing, a shaft rotatably mounted within said casing and extending longitudinally thereof and having one of its ends projecting beyond one end of said casing, a friction clutch rotatably mounted within said casing, means for shifting said shaft longitudinally within said casing, means for drivably connecting said shaft with said clutch when said shaft is longitudinally moved to one position 120 and means for connecting said shaft with said 125

casing against rotation when said shaft is longitudinally moved to another position.

7. A device of the class described comprising a tubular casing adapted to be held in the hand, a shaft rotatably mounted within said casing and extending longitudinally thereof and having one end projecting beyond one end of said casing, a driving element rotatably mounted within said casing, means for drivably connecting said shaft with said driving element and means on said shaft for detachably connecting a tubular element thereto.

8. A device of the class described, comprising a handle, a shaft rotatably carried by said handle and projecting from one end thereof, means for connecting said shaft for driving with a rotary source of power, and a winding spool detachably secured to said shaft.

9. A device of the class described, comprising a substantially straight tubular casing adapted to be held in the hand, a driving shaft rotatably mounted within said casing and extending longitudinally thereof and having one end projecting beyond one end of said casing, a clutch mounted within said casing and having one of its elements connected with a flexible driving member adapted to be connected with a rotary source of power, means on the exterior of said casing controllable by a finger for moving said shaft longitudinally of said casing to drivably connect said shaft with said clutch, and means for securing a rotary implement to the projecting end of said shaft.

35 10. A device of the class described, comprising a handle, a shaft rotatably carried by said handle and having a projecting end, means for connecting said shaft for driving with a rotary source of power, and means for 40 non-rotatably connecting said shaft with said handle.

11. A device of the class described, having in combination, an elongated casing, a shaft rotatably mounted within said casing having one of its ends projecting beyond one end of said casing, a clutch element rotatably mounted in said casing concentrically of said shaft, means for driving said clutch element, a sleeve loosely mounted on the intermediate 50 portion of said shaft and carrying a frictional clutch element engageable with said first mentioned clutch element, and means for connecting and disconnecting said shaft and said sleeve.

55 In testimony whereof we affix our signatures.

PAUL KUNIN.
